UNITED STATES PATENT OFFICE.

ADOLPH W. OSWALD, OF PHILADELPHIA, PENNSYLVANIA, ASSIGNOR OF ONE-HALF
TO JEAN JACQUES, OF PHILADELPHIA, PENNSYLVANIA.

CLOSURE FOR FILLER OPENINGS.

Application filed January 29, 1926. Serial No. 84,578.

This invention relates generally to closures for filling orifices while it has more particular reference to valvular caps embodying a plug valve interposed cross-wise of the filler passage.

The primary object of this invention is to provide a novel closure of the typified character which may be readily applied to storage tanks and other containers, with provision of free access for filling purposes; while when closed escape of the contents—or fumes arising therefrom—is effectively prevented.

Another object is to provide a valvular closure, of the kind above referred to, which is simple to construct, cheap to manufacture, and—withal—very effective in use.

With the foregoing and other objects in view, this invention embraces certain novel features of construction, combinations and arrangements of parts, hereinafter fully described; typically illustrated in the accompanying sheet of drawings; whereas the real essence and scope thereof is tersely defined by the appended claims.

In the drawings:—

Fig. I is a rear end view of a conventional type of automobile having my novel closure applied to the gasoline tank thereof.

Fig. II is a perspective view of the improved closure for filler openings, *per se*, in closed position.

Fig. III is a similar view showing the device in open position.

Fig. IV is a perspective view of the stationary portion of the closure device.

Fig. V is a similar illustration of the movable member or plug.

Fig. VI is a longitudinal section through the device; and,

Fig. VII is a transverse section taken substantially as indicated by the arrowed lines VII—VII on the preceding view.

Referring more in detail to the accompanying drawings it will be observed that my novel closure for filler openings comprises a stationary member or casing, comprehensively designated by the numeral 8, and a relatively movable portion or plug similarly indicated by the reference 9. The member or casing 8 conveniently—although not essentially—embodies a cylindrical body 10 having a slightly tapered bore with one end closed-in by an integral wall 11, as

well as including a somewhat enlarged offset or base 12 having a through passage 13 concentric with an inlet opening 14 in the opposed wall of said cylindrical body. Incidentally, the through passage 13 and inlet 60 opening 14 may be polygonal in contour so as to afford a maximum filling aperture; and, by way of example only, I have accordingly illustrated the same as hexagonal.

The offset or base 12, it will be remarked, is conveniently formed with an annular recess 15—for accommodation of a suitable gasket, not shown—whereby a concentric neck or extension 16 obtains, for a purpose later on specified; while it is screw-threaded 70 at 17 to engage a corresponding thread about the customary filler-opening nipple 18 of an automobile gasoline tank 19 for instance, as typically exemplified in Fig. 1. Again, the base 12 is polygonally configured at 20 for convenient engagement by a wrench in attaching or removing the device; while the aforesaid neck or extension 16 affords a commodious through passage 13 as well as protecting the threaded portion 17 from "flooding" when filling the tank 19, and—withal—providing an effective fluid and gas-tight seal at the nipple connection 18.

As a means effective to lock the device 85 against illicit removal I may employ one or more set screws 21, passed through a tapped opening or openings in the outer flange 22 of the annular recess 15; said screw or screws being subsequently sealed 90 in any of the well-known ways common to the art.

Referring now to the movable portion or plug 9, it will be seen that the same embodies a semi-cylindrical shell 23, conformably coned to the taper of the cylindrical body 10, with integral end pieces or walls 24, 25, respectively. Furthermore, the shell 23 is provided with a port or aperture 26 of complementary configuration to that of 95 the through passage 13 hereinbefore referred to, and with which it is adapted to register when the closure device is in the open position as later on explained. Attached to the outer end wall 25 is a separate 100 back piece 27 having an integral undulate projection or pair of diametrically aligned manipulating-wings 28 whereby the plug 9 is turned; as well as an arcuate segmental plate or apron 29 which serves as a cover 110

for the inlet opening 14 when the plug valve is in the closed position, as best shown in Figs. VI and VII. The aforesaid back piece 27 is, conveniently, attached to the 5 end wall 25 through the medium of an integral embossment 30 thereon engaging an axial aperture 31 in the contiguous end wall 25; said embossment 30 being formed with a co-extending lip flange 32 which is 10 appropriately swedged over, as shown in Fig. VI, to rigidly connect the parts 27, 25 together in an obvious manner.

As best shown in Figs. VI and VII, it will be seen that the end wall 24 of the plug 15 valve 9, opposite that attached to the back piece 27, is axially apertured at 33 to clear a concentric boss 34 inwardly projecting from the casing end wall 11. This boss 34 is axially bored and tapped to receive the 20 correspondingly threaded end of a shouldered retainer screw 35, intermediate the head 36 whereof and the plug valve end wall 24 there is interposed a star spring 37, whereby the plug valve 9 is always held in 25 fluid tight relation to its seat in the cylindrical body 10. The aforesaid screw head 36 is, conveniently, provided with a series of radial notches or holes 38 for application of an appropriate tool in assembling, 30 disassembling or adjusting, the plug valve 9 in an obvious manner. Furthermore it is observable that, by virtue of the location of the screw 35 wholly within the device, it is concealed against observation from the exterior and in a measure protected against 35 illicit tampering.

In order to limit movement of the plug valve 9, as well as to arrest the same against displacement by jarring or the like, I form 40 an arcuate recess 39 in the outer face of the inner end wall 24 thereof, as best shown in Fig. 5; said recess being—obviously—concentric with the axis of the plug. Fitted in the recess 39, and adjacent one end thereof, 45 is a coned stop 40 which, in conjunction with a similarly shaped stop 41 projecting inwardly from the cylinder casing end wall 11, serves to limit rotary motion of the plug 50 9; whereas, the stop 41 is adapted to ride over the stop 40 into the limited space intervening the latter and the adjacent end of the recess 39—due to the capacity for slight longitudinal movement of the plug valve 9 permitted by the star spring 37—in effecting 55 locking of the plug valve in closed position. Obviously, spring influenced buffer stops may be employed instead of the stops 40, 41, as will be well understood by those conver- 60 sant with the art without further description herein; while a stop pin 42 is preferably used in connection with the parts 25, 27 to ensure against relative rotation when swedging over the lip flange 32, as will likewise be well understood.

65 In use it will be apparent, on reference to

Figs. VI and VII more particularly, that when the device is in the closed position that the segmental plate or apron 29 snugly covers the inlet opening 14, while the semi-cylindrical shell portion 23 of the plug valve 70 simultaneously closes the through passage 13; whereby said device doubly seals the tank 19 against escape of fumes or gas arising therefrom. Concurrently, the port or aperture 26, in the shell portion of the plug valve 75 23, is located completely out of registration with the through passage 13, and by virtue of the friction fit of the plug 9 superinduced by the star spring 37, seepage of gas or fumes about the casing body 10 is likewise 80 prevented. On the other hand, when the plug valve 9 is given a quarter turn to the left-hand, as indicated by the arrow in Fig. VII, it will be readily seen that the segmental plate or apron 29 is swept clear of 85 the inlet opening 14, with concurrent movement of the aperture or port 26 into concentric registration over the through passage 13. Simultaneously with the movement just described that portion of the semi-cylindrical shell 23—previously closing the through 90 passage 13—is turned upwardly towards the left of Fig. VII until the longitudinal edge 43 thereof substantially aligns with the edge 44 of the casing body 10, whereas the apron 29 occupies the position best shown in Fig. 95 III. Obviously, the turning limits of the plug valve 9 are controlled by the arcuate recess 39 and co-operative stop 41, as hereinbefore set forth; whereas the stop 40 functions to retain said valve closed after the 100 manner described.

While the design and construction of closure for filler openings herein shown and described is deemed preferable, it is obvious 105 that in reducing this invention to practice detail changes will arise in adapting the same for different uses; accordingly, the right to all reasonable variations is hereby reserved, provided they are fairly comprehended within the scope of the subjoined claims.

Having thus described my invention, I claim:

1. A closure for filler openings comprising a body portion affording a through passage, said body portion having an annularly recessed base providing an inner concentric neck, a plug valve interposed cross-wise of the passage, an apron attached to the valve and adapted to normally cover the inlet to 115 said through passage, and means to yieldingly hold the plug valve in open position or lock the same in closed position.

2. A closure for filler openings comprising a body portion affording a through passage, 125 said body portion having an annularly recessed base providing an inner concentric neck, a plug valve interposed cross-wise of the passage, an apron secured on the valve and adapted to normally cover the inlet to 130

- said through passage, means yieldingly holding the valve seated, pin and slot means limiting rotation of the plug valve, and an auxiliary pin co-operative with said pin and slot means to axially trip said valve and to effect locking of the device in closed position. 5
3. A closure for filler openings comprising a body portion affording a through passage, 10 said body portion having an annularly recessed base providing an inner concentric neck, a plug valve interposed cross-wise of the passage, an apron secured on the valve and adapted to normally cover the inlet to 15 said through passage, pin and slot means limiting rotation of the plug valve, and an auxiliary pin co-operative with said pin and slot means to hold the valve in closed position but releasable by axial movement there- 20 of incidental to rotation in opening it. 25
4. A closure for filler openings comprising a cylindrical body affording a through passage and an inlet opening, said body having an annularly recessed base providing an inner concentric neck, a plug valve interposed cross-wise of the through passage, said valve having an attached apron and an opposed integral portion adapted to simultaneously close the through passage and inlet 30 opening, and means to yieldingly hold the plug valve in open or closed position. 35
5. A closure for filler openings comprising a cylindrical casing affording a through passage and an inlet opening, said casing having an annularly recessed base providing an inner concentric neck, a ported semi- cylindrical plug valve interposed cross-wise of the through passage, a winged back piece attached to the valve and having an apron at an angle relative to the valve port and 40 adapted to normally cover the casing inlet opening, and means yieldingly holding the valve seated with capacity for axial movement—incident to rotation—for effecting locking of said valve in the closed position. 45
6. A closure for filler openings comprising a body portion affording a through passage, and having an annularly recessed base providing an inner concentric neck, a plug valve having integral end walls interposed cross- 50 wise of the passage, a winged back piece attached to the valve and having an apron adapted to normally cover the inlet to said through passage, a pin and slot means limiting rotative movement of the valve, and a 55 co-operative stop effective to lock the valve in closed position.
7. A closure for filler openings comprising a body portion affording a through passage, a plug valve interposed cross-wise of the 60 passage, an apron on the valve adapted to normally cover the inlet to said through passage, a stop in the casing engaging an ar- cuate groove in the valve for limiting ro- 65 tative movement thereof, and a co-operative stop in said groove effective to axially move and lock the valve in closed position.

In testimony whereof, I have hereunto signed my name at Philadelphia, Pennsylvania, this 25th day of January, 1926.

ADOLPH W. OSWALD.
